VERNER LINDSJO, OF HOPEDALE, MASSACHUSETTS, ASSIGNOR TO DRAPER CORPORATION, OF HOPEDALE, MASSACHUSETTS, A CORPORATION OF MAINE

PICKER STICK CHECK

Application filed September 29, 1931. Serial No. 565,771.

This invention relates to looms, and more particularly to means for checking the movements of the picker stick.

It is customary to provide the picker sticks with check devices consisting of a loop member having side runs between which the picker stick oscillates as it alternately picks and checks the shuttle, and means for frictionally retarding the movement of the loop member. Ordinarily the side runs of the loop member are flat and positioned in a vertical plane.

It has been found that the picker stick at each end of its movement tends to pull these side runs down upon the supporting members therefor, resulting in very rapid wear of the loop member. It has also been proposed to position these side runs in a horizontal plane so that their broad surfaces were exposed to the aforementioned wearing action.

I have found that this construction is objectionable, for the reason that the sudden impact of the picker stick on the ends of the loop member will cause the side runs to crowd together and thus rub upon the picker stick, and wear both the stick and the loop member. I propose to overcome both of these difficulties by offsetting the objectionable lateral movements of the runs one against the other.

I accomplish this by positioning the friction exerting guides so as to hold portions at least of the plane surfaces of the side runs inclined downwardly and outwardly away from the plane of the picker stick.

A further objectionable feature of previous picker stick checks is that unintended variations in force of movements of the picker stick in one direction or the other, and the variations in the overthrow of the loop member as it is moved by the picker stick, cause the loop member to be variably positioned for its checking action. This, of course, results in an irregular and uneven checking of the shuttle with its attendant disadvantages.

It is accordingly an object of my invention to provide a picker stick check for looms comprising a loop member having side runs, portions at least of which are held in planes inclining downwardly and outwardly away

from the plane of the picker stick by means of friction exerting guides.

A further object of my invention is to provide means for always uniformly positioning the loop member of a picker stick check for its checking action.

Referring more particularly to the drawing:

Fig. 1 is a fragmentary view in elevation showing the right-hand end of a lay with a picker stick and the picker stick check embodying my invention, and

Fig. 2 is a vertical cross sectional view on line 2—2 of Fig. 1.

The usual lay 1 is shown as provided with a centre slot 2 within which oscillates picker stick 3. The picker stick is rocked about its foot portion from the full line position shown in Fig. 1 to the dotted line position, to pick the shuttle through the shed. The mechanism for so moving the picker stick is not illustrated or described as it forms no part of the present invention and many such mechanisms are well known in the art. When the shuttle is returned from the other side of the loom it moves the picker stick back to its initial position, and it is for gently slowing down and stopping this latter movement that the check is provided. The checking means for the picker stick consists of a loop member indicated generally at 4, which is comprised of side runs 5 of suitable oblong cross section, preferably rectangular, connected at their ends by any usual means, such as bolts 6 carrying leather washers 7.

This loop member is supported by guides which also serve to frictionally retard its movement. Each guide consists essentially of a bracket 8 having a pair of arms 9 and 10 extending toward the picker stick. The upper arm 10 is provided with a friction surface 11 which is inclined downwardly and outwardly away from the plane of the picker stick, the arm thus constituting one of a pair of opposed friction members. A set screw 12 extends through the lower arm 9 and has a smooth point 13 rotatably engaging an aperture in the other friction member 14. This friction member 14 is provided with a friction surface 15 which is parallel to the fric-

tion surface 11. The side runs of the loop member pass between these friction surfaces which hold portions at least of the side runs inclined in the same plane as the friction surfaces. Adjustment of the set screw serves to vary the friction exerted on the respective side run.

The angle of inclination of the friction surfaces may vary slightly with different types of looms, but is so proportioned that the tendency of the side runs to crowd together when the picker stick strikes the end of the loop member offsets the tendency of the downward pull on the end of the loop member to cause the side runs to be moved to the lower edges of their respective guides.

The length of the loop member is somewhat less than the extent of movement of the picker stick. The picker stick will, therefore, engage and move the loop member in opposite directions as it alternately picks and checks the shuttle. Varying conditions of operation may cause the picker stick to tend to overthrow in its picking direction to a greater or less extent, and the loop member may also overthrow in the same direction to varying extents.

In order to cause the loop member 4 to always stop at the same position at the inner end of its movement I have provided an element engaging the loop member and limiting the extent of its movement in the shuttle checking direction. This element, as shown, may consist of a flexible strap 16 engaging about the outer end of the loop member and secured at one end as at 17 to the lay. This element being flexible in nowise interferes with the normal action of the picker stick check, but does effectually limit its movement under abnormal operating conditions.

It is to be understood that the embodiment of my invention herein illustrated and described is for purposes of illustration only, and not of limitation, as the construction disclosed may be departed from in many respects without departing from the spirit of the invention.

I claim:

1. A picker stick check for looms comprising a loop member having flexible side runs of oblong cross section between which runs the picker stick oscillates, the picker stick engaging and moving the loop member in opposite directions as it alternately picks and checks the shuttle, a friction exerting guide for each side run of the loop member, each guide including opposed friction members having parallel contiguous surfaces engaging opposite sides of the respective run, said surfaces being inclined downwardly and outwardly away from the plane of the picker stick, and means for urging said friction members together.

2. A picker stick check for looms comprising a loop member having flexible side runs

of oblong cross section between which runs the picker stick oscillates, the picker stick engaging and moving the loop member in opposite directions as it alternately picks and checks the shuttle, a friction exerting guide for each side run of the loop member, each guide including a bracket having a pair of arms extending toward the picker stick, one arm constituting a friction member having its run engaging surface inclined downwardly away from the plane of the picker stick and the other arm carrying an adjustable friction member having a run engaging surface opposed and substantially parallel to said first mentioned surface.

3. A picker stick check for looms comprising a loop member having flexible side runs of oblong cross section between which runs the picker stick oscillates, the picker stick engaging and moving the loop member in opposite directions as it alternately picks and checks the shuttle and friction exerting guides holding at least a portion of the opposite side runs of the loop member oppositely inclined downwardly and outwardly away from the plane of the picker stick.

4. A picker stick check for looms comprising a loop member having connected side runs between which the picker stick oscillates, the picker stick engaging and moving the loop member in opposite directions as it alternately picks and checks the shuttle, a friction exerting guide for each side run of the loop member, each guide including opposed friction members having parallel contiguous surfaces inclined downwardly and outwardly away from the plane of the picker stick and means including a set screw for adjustably urging said friction members together, and an element engaging said loop member and limiting the extent of its movement in one direction.
